UNITED STATES PATENT OFFICE.

ROBERT WEHRLE, OF ST. LOUIS, MISSOURI.

MECHANICAL MOVEMENT.

SPECIFICATION forming part of Letters Patent No. 409,082, dated August 13, 1889.

Application filed September 28, 1888. Serial No. 286,681. (No model.)

To all whom it may concern:

Be it known that I, ROBERT WEHRLE, of the city of St. Louis, in the State of Missouri, have invented a certain new and useful Improvement in Mechanical Movements for Rock-Fans, &c., of which the following is a full, clear, and exact description, reference being had to the accompanying drawings, forming part of this specification.

This invention relates to a mechanical movement especially devised for actuating the rock-fans which, with their adjustable connecting devices, are the subject-matter of another application, Serial No. 286,682, of even date here-with, but may also be used for operating washing-machines, churns, &c.; and the invention consists in features of novelty hereinafter fully described, and pointed out in the claims.

Figure I is a vertical section and shows the works of the movement and the pulley-weight that operates it. Fig. II is a side view of the works in elevation. Fig. III is an enlarged section taken on line III III, Fig. I, and shows the sliding cut-off dog that locks the escapement-wheel between its pulsations. Fig. IV is an enlarged view of the cross-head or anchor of the adjustable pulsating bar that carries the detent which engages with the escapement-wheel. Fig. V is an enlarged view of the bottom section of the sectional actuating-weight and shows the screw-nut engaged on the bottom of the weight-rod and seated in a countersink in said section of the weight. Fig. VI is an enlarged transverse section taken on line VI VI, Fig. VII, and shows the tubular peripheral head-bearing of the rock-shaft that carries the cross-head of the pulsating bar; and Fig. VII is an end view of the same. Fig. VIII is an enlarged section taken on the line VIII VIII, Fig. I.

Referring to the drawings, in which similar figures of reference indicate like parts in all the views, 1 represents the back plate, and 2 the front plate, of the case that boxes in the works of the movement. 3 are the pedestals that connect said plates; 4, the screw-heads of said pedestals; 5, the screw-nuts that engage thereon and hold the plates together in their relative positions, and 6 are the screws by which the case is held to one of the walls of the cupboard or room to which it is attached.

7 represents the drum shaft or axle that carries the drum 8, around which is wound the actuating-cord 9 of the operating-weight 10. The said shaft has its bearings 11 relatively in the rear and front plates of the boxing, and said shaft is extended in front beyond the plate and squared to form the key-seat 12, by which the cord is wound around the drum and the weight elevated. The cord passes up from the drum around twin pulleys 13, whose trunnions 14 have bearings within the pendent arms 15 of the brackets 16, which are secured by screw-bolts 17 to the ceiling 18 of the cupboard or room in which the mechanical movement is erected.

The operating-weight 10 is of novel construction, being of adjustable weight, so as to be conformed to the power required contingent on the number and size of the fans to be actuated, or other machines—as for washing, churning, pumping, &c.—for which it may be used as a mechanical motor in the operation of the same.

The fast end of the cord is secured to the drum, around which it is wound by any suitable means, and its loose or reverse end is spliced or otherwise secured to the eyelet-loop 19 of the weight-carrier rod 20, and a screw-nut 21 is secured onto the screw-terminal of said carrier-rod. A series of sectional weights 22, (see Figs. I and V,) provided with slots or cut-aways 23, provide the means for adjusting the weight to accord with the power that it is required to use. The slots in the side of the sections are cut in to a little past the center, and thus provide the means for seating said weights on the pendent carrier-rod, they being placed thereon in the same way as the detachable weights of platform-scales. A countersink 24 is formed in the bottom of one of the sectional weights of sufficient size to receive the nut 21, and, that section being the first one placed on the rod, the nut is seated within said countersink. (See Fig. V.)

The main drive-gear wheel 25 has tight bearings on the drum-shaft 7, and next said drive-wheel, also with tight bearings on the same shaft, is the ratchet-wheel 26. The dog-pawl 27 has pivotal connection with one of the radial arms 28 of the drive-wheel by the bolt 29, which has its perforate seat in the

dog and in said arm of the drive-wheel, and a spring 30, secured by a pivot-pin 31 to another arm 28 of the drive-wheel, presses against and enforces the engagement of the 5 dog-pawl with the ratchet-wheel. As the weight is wound up from the winding of the cord around the drum by the action of the key, the dog-pawl acts as a follower, jumping the ratchet-teeth; but immediately that the 10 ratchet-wheel ceases to turn the spring impels the dog-pawl to engagement with the ratchet-teeth to hold the weight in its wound position, subject alone to its gradual unwind under the operation of its escapement devices while effecting the work that it is set 15 to perform.

The drive-wheel is provided with cogs 32 around its periphery, that mesh into engagement with the cogs 33 around the periphery 20 of the secondary drive-wheel 34, which has tight bearings on the shaft or axle 35, which axle has loose bearings 36 relatively in the rear and front plates 1 and 2, that box in the works of the movement. The cogs 33 of said 25 secondary drive-wheel also mesh into engagement with the cogs 37 of the pinion 38, which pinion has tight bearings on the shaft 39, on which shaft is also seated with tight bearings 30 the escapement-wheel 40. The said escapement has the usual ratchet-teeth 41 around its periphery, in which engages the 35 detent 42 of the pulsating or pendulum bar 43, that regulates the pulsations of the escapement. The said detent is secured between the vertical members 44 of the compound angle-arms of the cross-head 45 by 40 screw-bolts 46, that engage in their screw-seats in said arms and pass through said detent and through the re-enforcing spring 47, that backs up said detent, and yet allows elastic movement of the same within the limit of said vertical arms.

48 is an anti-rattler cushion located between the detent and the inner vertical arm 44, and which is held in its seat by the same bolts that secure the detent and its spring.

49 are the horizontal members of the angle-arms of the cross-head, that are coupled together by the set-screw bolt 50, which bolt 50 also passes through the elongated slot 51 in the buffer-bar 52, which buffer-bar is adjustable to limit the action of the toggle-link 53, which is pivoted to the projecting lug 54 by the bolt 55, which has loose bearings in one 55 end of the toggle-link and in said lug. A spur-lug 56, (that rises from the same end of said toggle-link,) when it bumps against said buffer-bar, limits the movement of the link in that direction. It will be seen that the 60 elongated slot in the buffer-bar provides means of adjustment of said bar by its elongated transposition when the set-screw 50 is loosened.

The rear journal of the shaft 57, on which 65 the cross-head of the pulsating or pendulum bar has tight bearings or is fast, has a loose bearing 58 in the rear plate of the case that

incloses the works, and around the front journal 59 of said shaft is a screw-threaded boss 60, secured in rear of the front plate. A 70 peripheral bearing 61 is provided for said front journal by the tubular journal-box 62, whose peripheral screw-thread 63 engages in its screw-seat 64 in the front plate 2 and in the boss 60 of the case that incloses the works, 75 and its square head 65 provides a hold for the wrench or key that screws it home in its seat. It will be seen that by the provision of this screw-adjustable journal-box the end 80 wear of the journals of the shaft is taken up, and thus the bearings of the pulsating detent of the escapement are readily adjusted. A screw-threaded duct 66 through the head of said journal-box into its tubular bearing provides the means for lubricating said bearing, and the screw-threaded stop-pin 67 closes 85 the mouth of the duct after the insertion of the lubricant by being screwed therein.

The pulsating or pendulum bar 43 below its cross-head is pivotally secured to the center of the adjustable coupling-yoke 68 by the bolt 69, which passes through the perforated end of said pulsating bar, a perforation in the center of said yoke, and the perforated upper end of the counterpoise pendent bar 95 70, which latter bar carries the counterpoise-weight 71, that may be provided with a slot 72, that enables it to run on said bar, and is adjustably located and secured thereon by the set-screw 73. Near each end of the yoke 100 is provided a curvilinear slot 74, and relatively in both the pulsating bar and counterpoise-bar, and passing through said curvilinear slots of the yoke, thumb set-screws 75 are seated, and when said bars are rightly 105 adjusted in their relative pendent lines by screwing home said thumb-screws their adjusted position is set.

76 represents a compound lever, whose set end has loose bearings on the pivot-pin 77, which pin is seated in and projects from the adjustable bed-plate 78. The bed-plate is secured to the rear plate that incloses the works by the set-screw 79, which passes through an elongated slot 80 in said bed-plate and is engaged in its screw-seat in said rear plate. A set-screw 81, which is screw-seated in a flanged projection of the said rear plate, is conformably set to any change of adjustment of the bed-plate, (as a take-up, consequent 110 on the wear of the pulsating correspondents of the escapement.)

The said adjustment is effected by loosening the set-screw 79, that passes through the slot 80, moving said bed-plate forward to bring 115 the detents into closer correspondence with the teeth of the escapement-wheel, and then retightening the set-screw 79 and screwing up the follower set-screw 81 into re-engagement with the back of the bed-plate.

82 represents the angle-flange guide-plates, that are secured to the rear plate of the incasement that incloses the works by the screws 83, which pass through the sockets 84

in the corner pedestals 85 of the flange guide-plates and engage in their screw-seats 86 in said rear plate. A sliding bed-plate 87, that carries the surmounting arm 91, to which is secured the detent-dog 92, (that is the coadjutant detent of that which is spring-seated within the parallel angle-arms of the pulsating cross-head 45,) works longitudinally on the track-flanges 93 of the guide-plates 82, whose surmounting flanges hold said bed-plate in its seat under the impulse of the lever 76, in which the pivot-pin 88 (that surmounts and is carried by said sliding bed-plate) has loose bearings in the ovate slot 89 in said lever.

The loose or operating end of the compound lever 76 is pivotally connected to the outer end of the aforesaid toggle-link 53 by the pivot-pin 90, and thus corresponding simultaneous action is maintained between the two escapement-detents 43 and 92. The detent-dog 92 is provided with a stiffening-plate 94, between which detent and plate is placed an anti-rattler cushion 95, of rubber, leather, or other suitable material, that, as does the similar anti-rattler cushion 48 of its coadjutant detent, (being a non-conductor of sound,) deadens the rattling tick of the escapement. A set-screw 96, that passes through the adjustment-slot 97 in the said detent, anti-rattler, and stiffening-plate, is secured in its screw-seat 98 in the arm 91, that carries said detent-dog, and thus the detent is fastened to its adjustment.

A curvilinear spring 99 engages in its perforate seat 100 in the projecting end of the pivot-pin 77, that carries the compound lever 76, and its stayed end engages with one of the pedestals 3, that hold the case together, and its operative end exerts a reactionary pressure against the pivot-pin 88, and thus re-enforces the back-throw of the compound lever ready for a renewed pulsation.

101 represents oiling pipes or tubes, and 102 receiving-cups at their mouths. The said pipes carry the lubricant to the journal-bearings, respectively, of the drum shaft or axle 7, the axle 35 of the secondary drive-wheel 34, and the axle 39 of the escapement-wheel 40. The running time for the one winding of the movement in rooms with twelve-foot ceilings is from nine to ten hours.

I claim as my invention—

1. In a mechanical movement for rock-fans, &c., the combination of the geared drive-wheels, the escapement-wheel, the shafts or axles that carry said wheels, the incasing-plates that inclose the power-works and that provide bearings for the said axles, the ratchet-wheel with tight bearings on the main drive-wheel shaft, the pawl 27 and its re-enforcing spring 30, which pawl dogs the teeth of the ratchet-wheel, the key-seat on said wheel-shaft, the drum on said shaft, the operating-cord that is wound on said drum, the twin pulleys over which said cord runs, the weight-carrier rod 20, that is suspended from said

cord, the sectional actuating-weight whose sections are seated on said carrier-rod, the said weight constructed of slotted sections 70 that provide the means to increase or diminish the weight to accord with the power it is required to exercise, the lower section being provided with a recessed boxing, in which the screw-nut rests that is seated on the bottom 75 of the carrier-rod, substantially as and for the purpose set forth.

2. In a mechanical movement for rock-fans, &c., the combination of the geared drive-wheels, the escapement-wheel, the shafts or 80 axles that carry said drive and escapement wheels, the incasing-plates that inclose said wheels and in which said axles have bearings, the pulsating or pendulum bar 43, the cross-head that surmounts said bar, the angle-arms 85 of said cross-head, the shaft or axle 57, that carries said cross-head and its pendent pulsating bar, the tubular journal-box 62, that is screw-seated in the outer incasing-plate and provides a peripheral front bearing for the 90 shaft or axle 57, the detent 42, its re-enforcing spring 47, and anti-rattler cushion 48, all three secured in the intervening space between the vertical angle-arms 44 of said cross-head, the coupling-yoke 68, provided with 95 curved slots 74, the counterpoise-bar 70, the pivot-bolt 69, that connects the pulsating bar, the counterpoise-bar 70, and the coupling-yoke, the adjustable weight and set-screw secured to the counterpoise-bar, and the thumb 100 set-screws 75, that adjust the relative positions of said bars and yokes to influence the action of the detent in its pulsations with the teeth of the escapement-wheel, substantially as and for the purpose set forth.

3. In a mechanical movement for rock-fans, &c., the combination of the geared drive-wheels, the escapement-wheel, the detent, the cross-head, the pulsating bar, the yoke, the counterpoise-bar, the compound lever 76, the 110 coadjutary dog-pawl said lever actuates, the anti-rattler cushion attached to said dog-pawl, the sliding bed-plate that carries said dog and by the influence of the lever enforces the periodic engagement of the dog with the teeth 115 of the escapement-wheel in unison with the action of the detent, the flanged plates 82, that guide the sliding dog-plate 87, the toggle-link 53, that pivotally connects the compound lever to the angle-arms of the cross-head and 120 enforces the unison of their pulsations, the adjustable buffer-bar 52, and the spur-lug 56 on the toggle-link, that together limit and adjust the movement of the compound lever and pulsating bar, substantially as and for 125 the purpose set forth.

4. In a mechanical movement for rock-fans, &c., the combination of the drive-gear and escapement-wheels, the shafts or axles that carry said wheels, the rear and front incasing-plates that inclose said wheels and in which are provided bearings for the journals of said shafts or axles, the tubes or pipes that carry lubricant to said bearings, the pul-

sating bar 43, the cross-head that surmounts said bar, the angle-arms of said cross-head, and the detent 42, anti-rattler cushion, and enforcing-spring that are secured between the 5 angle-arms of said cross-head, substantially as and for the purpose set forth.

5. In a mechanical movement for rock-fans, &c., the escapement-wheel, the detent, the cross-head that carries the detent, the adjustable pulsating bar that carries the cross-head 10 45, the toggle-link 53, the compound lever 76, that is connected to the pulsating cross-head,

the pivot-pin 77, on which said lever works, the spring seated in said pivot-pin that aids the reactionary movement of the lever, the 15 adjustable bed-plate 78, that carries said pivot-pin, the set-screw that secures it, and the set-screw 81, that holds against the back of said bed-plate, substantially as and for the purpose set forth.

ROBERT WEHRLE.
